UNITED STATES PATENT OFFICE.

EDGAR H. BETTS, OF TROY, NEW YORK, ASSIGNOR TO EARL & WILSON, OF TROY, NEW YORK, A CORPORATION OF NEW YORK.

COLLAR-SUPPORTING DEVICE FOR SHOW-CASES.

1,120,122.

Specification of Letters Patent.

Patented Dec. 8, 1914.

Application filed June 14, 1913. Serial No. 773,611.

To all whom it may concern:

Be it known that I, EDGAR H. BETTS, a citizen of the United States, residing at Troy, in the county of Rensselaer and State 5 of New York, have invented certain new and useful Improvements in Collar-Supporting Devices for Show-Cases, of which the following is a full, clear, and exact description.

10 In displaying collars in the usual way, by mounting in vertical and horizontal rows in an upright showcase, they are usually fastened only at a single point, at the back, and in consequence some of them sag in 15 front, or become tilted to one side or the other, with the result that the display is rendered unsightly instead of having the neat and attractive appearance desired.

My present invention is designed to overcome these defects, and its chief object is to 20 provide a device which will support the collar both at front and back, thereby preventing the front from lopping or sagging, and also to support the collar on each side of its 25 center at the back so as to prevent lateral tilting.

To this and other ends the invention consists in the novel features of construction and combinations of elements hereinafter 30 described.

One form of the invention is illustrated in the accompanying drawing, in which— Figure 1 shows the complete device in 35 perspective. Fig. 2 is a central section of a turn-down collar of the usual style, supported by my device, which is shown partly in section. Fig. 3 is a plan view of the device, with a portion of the collar in horizontal section. Fig. 4 is a bottom plan view 40 of the blank from which the rear portion of the support is made.

As shown best in Figs. 1 and 2, the rear portion of the collar support comprises a wide flat base-plate 10 upon which the lower 45 edge of the collar rests. said plate extending laterally for some distance on each side of the center of the collar. At the rest is a horizontal extension or tongue 11 having an upright finger 12 provided at its top with an aperture 13 to receive a screw or other fastening by which the device can be secured to the back of the show case. At the forward end of the extension 11 is a vertical

finger 14 and integral with the front edge of the base 10 is a vertical front plate 15. 55 As shown in Figs. 2 and 3, the rear portion of the collar fits down upon the base plate 10 between the finger 14 and the plate 15, the "spring" or resiliency of the plate 16, co-operating with the rigid finger 14, being 60 sufficient to hold the collar securely, while the base 10, extending laterally on each side of the central finger 14, prevents tilting of the collar to one side or the other. For additional security the plate 10 may, if desired, 65 be provided with vertical flanges 17 at its rear edge, on each side of the extension 11. The plate is an important feature of the device, as it not only serves as part of the collar-holding device but also may be in the 70 form of a trademark or other advertising device, or the name or style of the collar, etc., as indicated in Fig. 1, in which a well known trademark is illustrated, appearing in silhouette against the collar shown in the 75 dotted lines.

The supporting devices described above, comprising the base plate 10, extension 11, etc., is preferably made of a single piece of sheet metal by stamping out a blank and 80 bending the same to proper shape. Such a blank is shown in Fig. 4, from which it will be seen that the central longitudinal extensions 12^a and 14^a are bent downwardly at right angles on the dotted lines 12^b, 14^b, to 85 form the fingers 12 and 14, and the part 15^a is bent down on the dotted lines 15^b to form the plate 15. The body portion 10^a of the blank, which portion afterward forms the base-plate 10, is slit rearwardly at 10^b on 90 each side of the extension 14^a so as to carry the inner end of the same back to the rear edge of said body portion and to the front end of the part 11^a which afterward constitutes the horizontal portion 11. At its 95 rear the body portion is slit forwardly at 10^c on each side of the extension 10^a to provide edge-portions 17^a which are bent down at right angles along the dotted lines 17^b to form the flanges 17. At the base of the 100 extension 14^a is a transversely elongated aperture 18, and at the base of the extension 12^a is a similar aperture 19, the two apertures being arranged in alignment as shown, so that when the parts in which they are 105 formed are bent as described the apertures

will be in register. Outwardly beyond the aperture 19, in the same part 12^a, is another aperture, designated at 20, which in the completed device occupies a position directly above the aperture 19.

The front of the collar is supported by a horizontal bar 21, preferably of stiff spring-metal, extending forwardly from the rear supporting device. At its rear the bar extends through the apertures 18 and 19, and has its end turned up and hooked into the aperture 20, thereby securing the parts firmly together. At its front end the bar has fixed to it a suitable fastening device for 15 engaging the front button hole of the collar, as for example one of the separable stud type shown at 22.

The method of mounting the collar in the device is shown in Fig. 2, in which 23 designates the collar.

The device is simple and inexpensive, and in use supports the collar in a fixed position without sagging or tilting, thereby keeping the show-case display in a slightly 25 condition.

What I claim is:

A collar-support for the purpose described, comprising a one-piece sheet-metal device having a transversely extending base with an integral name-plate on its forward edge, a rear extension integral with the base, 30 a vertical finger integral with the extension at the rear thereof for attachment to a suitable support and an integral vertical finger at the front of said extensions, said vertical 35 fingers having horizontally aligned apertures at their bottoms; a horizontal bar attached to the aforesaid rear finger and extending forwardly through the said apertures in the two fingers; and a fastening device on the front end of the bar to engage the front of a collar.

In testimony whereof I affix my signature in the presence of two subscribing witnesses.

EDGAR H. BETTS.
